INVENTOR

Alfred W. Boreham

BY

ATTORNEY

UNITED STATES PATENT OFFICE

ALFRED WALTER BOREHAM, OF CHEAM, ENGLAND

GAITER OR LEGGING

Application filed September 14, 1931, Serial No. 562,813, and in Great Britain August 21, 1931.

This invention relates to leggings or gaitsers and has for its object to provide an improved construction and arrangement which can be easily and quickly fitted into place and secured by the use of a single fastening device.

According to the invention a legging or gaiter comprises a piece of leather adapted to be wrapped around the leg and fixed in position by a single fastening device located at or near the upper end.

According to the preferred form of the invention a legging or gaiter comprises a portion adapted to be wrapped around the ankles, a portion continuous therewith adapted to be wrapped around the leg and a single fastening device for securing the whole gaiter in position, the portion carrying the fastening being so shaped that the remainder of the gaiter from ankle upwards is prevented from working loose during wear.

Reference will now be made to the accompanying drawing which illustrates by way of example a gaiter constructed according to the invention and in which:

Fig. 1 is a view showing the gaiter unwrapped.

Fig. 2 shows the first stage of wrapping the gaiter in position and

Fig. 3 shows the gaiter fixed in position.

Referring first to Fig. 1 the gaiter comprises a sheet of leather *a* the inner surface of which is shown in the drawing and the edge *b* of which forms the upper edge of the gaiter when in its operative position (see Fig. 3). The lower portion of the leather sheet *a* is provided with a reinforcement *c* covering that portion of the gaiter which in use makes contact with the boot. The reinforcing strip *c* tapers upwards to a point *d* which serves for positioning the gaiter as this point is intended to lie immediately at the back of the boot. Adjacent the reinforcement *c* a piece of soft leather *e* is secured along one edge of the main portion *a*. This soft leather flap is passed around the front of the leg and pushed between the leg and the reinforcement *c* so as to cling to the ankles and prevent displacement during fitting of the gaiter. This position is shown in Fig. 2.

The external surface of the main portion *a* is provided with a strap *f* and buckle *g* (shown in broken lines in Fig. 1) for fastening the gaiter in position.

After fitting to the stage shown in Fig. 2 that portion of the gaiter which remains free, is of substantially triangular shape and formed slightly concave so as to fit snugly around the calf of the leg and this fitting may be facilitated by a slit *h*. This portion is wrapped around the leg until it can be fastened by means of the buckle *g* and strap *f* in the position shown in Fig. 3. When in this position the edge *b* encircles the leg and the adjacent edge *i* extends in a helical direction, this edge being held tightly against the leg by the fastening and preventing the lower portions of the gaiter from working loose during wear.

The invention can also be applied to anklets of leather or other material used with shooting boots or the like in which case the use of the flap of soft leather is optional and a pair of eyelets is preferably disposed near the lower edge so as to engage the anklet with the boot lace. Otherwise the anklet is wrapped and fastened with a single fastening in the same manner as the legging above described.

The gaiter possesses the advantages that owing to the necessity for only one fastening it can be easily and quickly fitted and that it cannot work loose in wear. Also by providing a number of holes in the strap *f* it is possible to make gaiters of a standard pattern adjustable to the requirements of different persons. The invention is not limited to the use of a strap and buckle as other means of making an adjustable connection may be employed.

I claim:

1. A legging or gaiter comprising a substantially triangular piece of leather, a flap of soft leather attached to and extending beyond one edge thereof and adapted to be overlapped and pressed upon by the outer wrapping of the leather when the latter is wrapped to thereby aid in holding the legging in position, a reinforcement extending partly over the inner surface from the edge

adjacent the soft leather flap and a fastening device the components of which are disposed on the edge of the piece remote from said reinforcement.

3 2. A legging or gaiter comprising a sheet of substantially triangular shape adapted to be wrapped about the leg, a soft flap projecting beyond one edge of the sheet and adapted to be overlapped by the wrapped sheet to cause the legging to cling to the ankle through the pressure upon the wrapping of the sheet, and fastening means to secure the sheet against unwrapping.

70

75

3. A legging or gaiter comprising a substantially triangular sheet adapted to be wrapped about the leg with the hypotenuse disposed helically, a soft flap projecting beyond one of the other edges of the sheet and adapted to be overlapped and pressed upon by the wrapped sheet, and a position-indicating reinforcement along the hypotenuse edge relatively close to said flap, and means to secure the sheet against unwrapping.

In testimony whereof I have hereunto set my hand.

ALFRED WALTER BOREHAM.
